UNITED STATES PATENT OFFICE.

FRANK BATTER, OF PORTLAND, OREGON.

TIMING APPARATUS FOR MOUNTAIN-AIR SANITARIUMS.

Original application filed May 21, 1920, Serial No. 383,180. Divided and this application filed August 28, 1922. Serial No. 584,923.

To all whom it may concern:

Be it known that I, FRANK BATTER, a citizen of the United States, and a resident of Portland, county of Multnomah and State 5 of Oregon, have invented a new and useful Improvement in Timing Apparatus for Mountain-Air Sanitariums, of which the following is a specification.

This invention relates to structures in 10 which can be artificially maintained such atmospheric conditions of temperature, pressure, humidity and so forth as may be dictated by the state of a patient. This invention controls the duration of any given 15 atmospheric condition and the time required to reach it and also the time required to pass from one such condition to another and if desired, the time can be predetermined in which the patient can live normally without 20 interference with such prescribed regimen. Previous patents of mine, No. 904,172; 1,107,744; and 1,107,745 have dealt with atmospheric pressure or rarefied conditions for simulation of high altitude.

25 This application is being filed to cover the patentable subject matter divided out of the application filed by myself on May 21, 1920, Serial No. 383,180, for portable mountain air sanitarium and therapeutic process 30 for use therein, and is a continuation in part of the latter with respect to the subject matter divided out of the same.

The specific object of my present invention, however, is to provide a timing mechanism which will control the air valve in a structure of this character and by the use of which it is possible to simulate a trip at a predetermined speed to a predetermined altitude, a stay at that altitude for a predetermined time and return therefrom at a predetermined speed.

40 A further object is to provide manual means which may be brought into play to supersede the automatic control of the timing mechanism so that a given condition may be maintained for as long a time as desired and also that a change to a higher or return to a lower altitude may be quickly accomplished by manual means.

45 These and other objects are accomplished in the accompanying drawings, in which:

50 Fig. 1 is an elevation of my timing device and which also shows the valve and portion of the pipe which the valve controls;

Fig. 2 is a section of the valve taken on the line 2-2 of Fig. 1;

Fig. 3 is a section of the valve taken on the line 3-3 of Fig. 2;

Fig. 4 is a section taken on the line 4-4 60 of Fig. 3;

Fig. 5 is a section taken on the line 5-5 of Fig. 1 and shows the governing mechanism which regulates the rate of speed at which the timing mechanism travels; 65

Fig. 6 is a line taken on the line 6-6 of Fig. 5 and shows a section of the governor taken on the line normal to the one on which Fig. 5 was taken;

Fig. 7 is an enlarged view of the drum 70 and winding mechanism of my device;

Fig. 8 is a side elevation of the same parts as shown in Fig. 7;

Fig. 9 is a longitudinal section of one of the counterbalancing weights of my in- 75 vention;

Fig. 10 is a section taken on the line 10-10 of Fig. 9; and

Fig. 11 is a section taken on the line 11-11 of Fig. 9. 80

The function of the timing mechanism is to control the main valve 10. This valve is opened and closed, and a duration of its location in any given position is determined by this timer and control apparatus 85 which may be said to operate in a predetermined manner without precluding control of the operation to vary the conditions. The control apparatus has three separate timers, A, B and C. A acts to open the 90 valve at a rate which may be varied. B acts to determine the length of time during which the valve shall occupy the positions to which it has been moved by timer A and C acts to close the valve at a rate 95 which also may be varied. Each position of the valve 10 represents a particular barometric pressure of a certain altitude.

This is calibrated on vertical scales which are adjacent and form a part of the control mechanism in the timer. Each of the timers A, B and C are similar and involve similar mechanism but are connected to perform differently on the valve. A and C rotate the valve in opposite directions and 100 B holds the closing means from operating 105 for a predetermined length of time. The main valve 10 is made preferably in the form of a gate valve having a gate 11 which co-acts with the body 12. The open- 110

ing controlled by the gate 11, as can be seen in Fig. 2, is made with an enlarged part 13, the sides of which converge towards the narrower and uniform part 14, the result being that as the valve begins to close the volume of air passing thru the valve decreases rather rapidly for a given movement of the gate until the uniform part of the opening is reached and the reverse of this operation occurs in the opening of the valve.

For the sake of safety a complete shut-off of ventilation by closing the valve is prevented by the by-pass 15 which is necessarily open at all times, because the web 16 prevents the valve 11 from passing down over the same. The gate 11 is lowered by a threaded valve stem 17 passing up thru the stuffing box 18, the stem 17 being provided with a pair of ratchets 19 and 20 each of which has two sets of ratchet faces as 19^a and 19^b, the teeth of which are set opposed to each other. The offset pawl 21 co-acts with the ratchet teeth. In one position it acts with the outer teeth 19^a and in the other position it co-acts with the inner ratchet teeth 19^b and thus in the opposite throws causes the stem 17 to be rotated in opposite directions. The sheaves 22 and 23 are also positioned on the stem 17 and are arranged so that the driving chains can pass over them and thus connect the mechanism to the valve. The driving sheave 22 connects with the ratchet 19 and its pawl 21 and the sheave 23 connects with the ratchet 20 and its driving pawl 24. The valve and valve stem with its connecting mechanism are all suitably supported and braced by the frame 1 of the timer.

The timer A is similar to timers B and C and thus the parts that constitute the timer A are the counter parts of the ones in the other two timers unless otherwise noted. The frame 1 houses the entire control and indicating mechanism and also supports the valve stem and thus the mechanism is practically encased on at least three sides. The endless chain 2 is mounted over the sheave 23 on the valve stem 17 over the idler sheave 3 and around the winding drum 4 so that whenever the drum rotates it moves the chain 2 and thus rotates the sheaves 23 on the valve stem 17. The drum 4 is made with a grooved periphery, the grooves 5 being adapted to hold the wound portion of the cable 6 which leads to the indicating mechanism. The drum is connected to the governor mechanism thru the ratchet and pawl mechanism 7. The drum 4 is rotatably mounted on the shaft 8 which rests in bearings 9 which are fastened to the frame 1. Gears 25 and 26 are fixed to the shaft 8 and the gear 25 holds the pawl of the mechanism 7 and the drum holds the ratchet. The pawl is held in engagement

with the ratchet by spring 27 and thus when the pawl is in position and the gear is rotated it rotates the drum in one direction. The gear 25 meshes with the pinion 28 which is mounted in the shaft 29. A large gear 30 is also mounted on the shaft and meshes with the small gear 31 which is mounted on the shaft 32. A large gear 33 is also mounted on the shaft 32 and meshes with the pinion 34 mounted on the shaft 35. All of these shafts are journaled in suitable boxes mounted on the frame 1.

The train of gears 28 to 34 inclusive serve to reduce speed of rotation of the drum 4 in relation to the crank disk 36 which is mounted on the shaft 35. Crank disk 36 has a pin 37 near its periphery which is connected to a piston rod 38. The crank disk is counterbalanced by a counter weight as 39 which is of sufficient weight to balance the piston rod 38. The governing mechanism is connected to the piston rod 38 which regulates the rate of speed at which the mechanism moves. Many types of governors can be used but I have found from experimentation that the preferable type is embodied in Figs. 5 to 6 of the drawings, and consist of two open end containers as 40 and 41 which telescope one into the other. The container 41 is perforated as at 42, and the telescope sections are fastened to a rod 38. The assembled rod with the containers placed thereon is inserted in a cylinder 43 which is partially filled with liquid. This cylinder is pivoted as at 44 so that it can align itself to the rod 38 at all points during the stroke of the same. The cylinder has a false bottom 45 with a hole 46 in the center which is suitably packed and adapted to permit the piston rod to slide there thru without the loss of any appreciable amount of liquid from the container. The top of the container 40 has a plurality of air vents as 47. Telescope containers are so arranged that the buoyancy will slightly more than counterbalance the effect of the force of the machine in operation so that if the sections are telescoped completely within one another the governor will not operate because the buoyancy in the containers will more than counterbalance the force of the work intended to be done in the machine. It is necessary that the section 41 be extended from out the wall of the section 40 so that the perforations will be uncovered. Uncovering a row of perforations will permit a small quantity of the water to be received within the container which will directly affect the buoyancy and allow the containers to slowly sink in the liquid. When the containers are filled with liquid and the mechanism tends to draw the same out again the weight of the water held within the telescope sections will also prevent the disk 36 from rotating until the water

in the cylinder has seeped out from the perforations 42. The governor will therefore rotate the mechanism in inverse relation to the number of holes uncovered. An indicating rod 48 is fixed to the container 40 and registers on a gauge 49 which can be calibrated to measure directly the speed at which it is wished the device to work. The power for moving the mechanism is received from the weight 50 which is connected to the cable 6 which is wound around the drum 4. As the weight slowly falls the drum is rotated and as has been explained, works against the retardation of the governor mechanism. The cable 6 is mounted over suitable pulleys as 51 and is held in alignment with its proper groove by the mechanism controlled by the counter weight 52. This mechanism consists of a finger 53 which rides in the groove in the drum. This finger is rigidly mounted to a carriage 54 which is guided by cross rods 55 which are fixed to the frame 1. A pulley 56 is also mounted to this carriage and is positioned so as to be vertically aligned with the groove which the cable is supposed to be mounted over. The counter-weight 52 is attached to the frame 54 and is equal in weight so as to counteract the normal tension of the cable 6 and also the friction of the carriage 54.

The timers B and C are rendered inoperative because the friction brake shoes 57 and 58 bear respectively on the crank disks 36^a and 36^b. The brake shoe 57 is connected to the rod 59^a which is pivotally connected to the fulcrumed lever 59 which is fastened on its opposite end to the counterweighted rod 60. The counter weight 61 is fastened to this rod by another fulcrumed lever 62 so that the action of this lever on the rod 60 causes the friction lever to be braced against the disk 36^a. The disk 36^b is similarly held in inoperative position by the friction shoe 58 being placed thereon. This friction shoe 58 is connected to the rod 62 which is connected to the lever 63 which in turn is connected to the counterweighted rod 64, the counterweight 65 acting with the rod 64 and being mounted on the lever 66. The levers are all fulcrumed on the frame 1, levers 62 and 66 being positioned upon the bottom and levers 59 and 63 being fulcrumed on the top. The levers 62 and 66 have notches 62^a and 66^a respectively, by which the effect of the counterweight 61 and 65 can be adjusted so as to exert different forces of the friction blocks against their respective disks.

The timing apparatus operates as follows: In the operative position of the control apparatus the respective weights A', B', C' are supported in their highest position by the grids on the stationary rods adjusted to their highest position. The valve

10 is then open. If it is desired to simulate a trip to an altitude of four thousand feet the grid 67 is adjusted on the counterweighted rod 60 until its pointer is opposite four thousand feet on the scale 68. The grid 69 is moved down out of the way and the timer A starts to close the valve. The grid 70 is adjusted on the counterweighted rod 64 to the desired point on the time scale 71, such as for example, three days. This scale can be calibrated in days, hours or months or any other standard unit of time which it is most common to maintain.

The grid 70^a is adjustably mounted on the fixed rod 64^a and is adapted to hold the weight B'. If this grid is uppermost the weight will be held indefinitely in one position and the relative pressure will correspond to the altitude indicated on the scale 71.

The grid 72 which is mounted on the rod 73 indicates on the scale 74. This grid is adjusted so as to indicate zero feet on the altitude scale 74 which indicates atmospheric pressure. The device is then set and when the grid 69 is removed from under the weight A' the weight will slowly descend and will start the timer in operation. The weights B' and C' are held at the top because of the friction shoes previously described. The falling weight having started will continue until it reaches the grid 67 and during this time the valve 10 will be moved towards closed position because of the gearing connections already described. When the weight A' strikes the grid 67 the weight will more than balance the counter weight 61 and this will cause the rod 60 to be depressed. Depressing this rod allows the brake shoe 57 to be released and allows the timer B to operate. The timer B as already noted, controls the length of time which the valve is held rotated in operative position and thus until the weight B' strikes the grid 70 the air in the room controlled by the valve 10 will be held at a decreased pressure which corresponds to the altitude registered by the indicator 67. When the weight strikes the grid 70 it also is heavy enough to overbalance the counter-weight 65 and thus the rod 64 is depressed and thru the action of the lever 63 allows the brake shoe 58 to be removed from the disk 36^b and this action permits the timer mechanism C to operate. The weight C' is then permitted to fall freely and it continues to do so until the weight C' rests on the grid 72. If the grid 72 is set so as to indicate zero feet or atmospheric pressure the pressure in the room corresponds with atmospheric pressure and therefore no differential in pressure exists. In this way a trip at a predetermined speed to a predetermined altitude, a stay at the altitude for a predetermined time and return therefrom at a predeter-

115
120
125
130

mined speed may be simulated. If, however, it should prove desirable, as for instance, because of a change in the condition of the patient to alter the original plans the various grids adjustable on the fixed rod, or any of them, may be brought into play to supersede the automatic control so that a given condition may be maintained for as long or short a time as desired, and the change to 10 a higher or return to a lower altitude may be manually as well as automatically controlled by the following mechanism: This is accomplished by the handle 75. This is mounted on a transverse rod 76 and has 15 fixed thereon three pinions 77^a, 77^b, and 77^c, which may be adjusted so as to mesh with any of the three gears 26, 26^a, 26^b, so that they may be rotated separately from the automatic control mechanism. This rod 76 20 is slidably mounted in bearings 78. If the weight A' is partly down and it is desired to bring it up quickly it may be done by rotating the handle 75 and meshing the pinion 77 with the gear 26 on the timer A and reversing the pawls 24 and 21 so that they will cause the valve to be opened independently of the action of the weights and will also raise the weight A' to its uppermost position. Reversing the pawls to their original 25 position renders the mechanism in readiness to be operated and controlled by the automatic mechanism. This same mechanism can be used to reverse the operation of the timer C and in this case the pinion 77^c can be 30 meshed with the gear 26^c and the action of the weight C' be reversed. The weights A' and B' are provided with devices by which the force of the blow striking the grid can be minimized and also that the action of the 35 releasing means will be sudden and not gradual so that the time of change can be estimated closely. The weights are hollow providing a cylinder 79 in which a piston 80 works. This piston is fitted snugly so 40 as to eliminate substantially all of the leakage when it is moved in the cylinder. The piston is connected with a rod 81 and the cable 6 is connected thereto. The rod 81 passes thru the stuffing box 82 which prevents 45 and substantial leakage. The piston 80 is normally held in its lowermost position by the latch 83 which is held in place by the spring 84. A wedge shaped member 85 extends below the timer A' and thus when the 50 weight approaches the grid this wedge shaped member 85 will strike first. When the member strikes the grid it is pushed upward and forces the lug 86 outward which moves the latch 83 away from the piston 80 55 and allows the piston to move in the cylinder 79. Thus the weight does not strike the grid heavily but the compression of the air provides a cushion in the cylinder and thus eliminates the jar. A combination pet cock and check valve 87 is provided to control 60

the air imprisoned by the piston 80 in cylinder 79. the grids, and especially the grids 70 and 70^a are made with a plurality of prongs and these prongs are so spaced that they pass readily between the prongs on the 70 opposite grid as shown in Fig. 11 so that these grids may be moved by each other without interference.

I claim:

1. In a main air control for a sanitarium, 75 a rarefaction valve, a series of timers each provided with a motor and a stop for co-operation with a movable element thereof, operative connections between said first motor and valve for moving the same toward closed position, operative connections between the third of said motors and said valve for moving it toward open position, the stops of the first and second motors having a limited movement, brakes for the second and third motors, and operative connections between said movable stops and the brake of the adjacent motor to release the same on operation of the stop.

2. In an air control for a sanitarium, a rarefaction valve, a timer, operative connections between said timer and valve to move the valve toward closed position, a second timer, operative adjustable connections between the first timer and the second timer 95 for releasing the same as the first timer stops, a third timer, operative connections between said third timer and valve to move the valve toward open position, and operative connections between the second timer 100 and the third for releasing the same as the second timer stops.

3. In an air control for a sanitarium, a rarefaction valve, three timers, each provided with a motor and with a stop for said motor, operative connections between the first timer and the valve for moving the same toward closed position, operative connections between the third timer and valve for moving the valve toward open position, the second and third timers being provided with brakes and the stops of the first and second timers having a limited movement, operative connections between the movable stop of the first timer and the brake of the second timer, operative connections between the movable stop of the second timer and the brake of the third timer, and a stop for the third timer.

4. In an air control for a sanitarium, a rarefaction valve, three timers, each provided with a motor and with a stop for said motor, operative connections between the first timer and the valve for moving the same toward closed position, operative connections between the third timer and valve for moving the valve toward open position, the second and third timers being provided with brakes and the stops of the first and second timers being counterbalanced and 130

having a limited movement, operative connections between the movable stop of the first timer and the brake of the second timer, operative connections between the movable stop of the second timer and the brake of the third timer, said connections permitting slight lost motion, and a stop for the third timer.

5. In an air control for a sanitarium, a rarefaction valve, a series of timers each provided with a drum and weight motor and a grid below the weight for intercepting the same, said grid being adjustable but otherwise immovable, the first two of 10 said timers having also adjustable grids below the weights for intercepting the same mounted on movable counterbalanced rods the fingers of the grids being displaced with reference to each other so that the pairs of 15 grids may pass without interference, and operative connections between each of said 20 last named grids and the timer next succeeding it.

6. In an air control for a sanitarium, a rarefaction valve, a timer, operative connections 25 between said timer and valve to move the valve toward closed position, a second timer, a third timer, and operative connections 30 between said third timer and valve to move the valve toward open position, said first and third timers being provided with adjustable stops having pointers, altitude

scales with which said pointers co-operate, 35 said scales being calibrated to indicate altitudes which will be simulated in the sanitarium when the pointers are in different positions.

7. In an air control for a sanitarium, a rarefaction valve, three timers, a stop for the first timer, a stop for the second timer, 40 operative connections between the stop of the first timer and the second timer for starting it when the first stops, operative connections between the stop of the second timer and the third timer for starting it 45 when the second timer stops, independent manually adjustable stops for each timer, and altitude scales for the stops of said first and third timers.

8. In an air control for a sanitarium, a rarefaction valve, three timers, a stop for the first timer, a stop for the second timer, 50 operative connections between the stop of the first timer and the second timer for starting it when the first stops, operative 55 connections between the stop of the second timer and the third timer for starting it when the second timer stops, independent manually adjustable stops for each timer, and altitude scales for the stops of said first 60 and third timers, the stops of the second timer being provided with pointers playing over time scales.

FRANK BATTER.
